(73) Assignee: **Bridgestone Corporation**, Tokyo (JP)

(57) **CLAIM**

(***) Term: **14 Years**

The ornamental design for a tread portion of a motorcycle tire, as shown and described.

(21) Appl. No.: **29/228,736**

DESCRIPTION

(22) Filed: **Apr. 28, 2005**

(30) **Foreign Application Priority Data**

Oct. 29, 2004 (JP) .....

2004-033066
FIG. 1 is a perspective view of the front and left side of a tread portion of a motorcycle tire showing our new design, it being understood that the tread pattern repeats itself uniformly throughout the circumference of the tire;

(51) **LOC (8) Cl.** .....

12-15
FIG. 2 is a front elevational view thereof, the top and bottom plan views being identical thereto;

(52) **U.S. Cl.** .....

D12/535
FIG. 3 is a rear elevational view thereof;

(58) **Field of Classification Search** .....

D12/534, D12/535, 536, 537, 544, 569, 570, 571, 572,
D12/579; 152/209.1, 209.9, 209.11, 209.12,

152/209.28

FIG. 4 is a right side elevational view thereof;
FIG. 5 is a left side elevational view thereof;

See application file for complete search history.

FIG. 6 is an enlarged fragmentary front elevational view thereof; and,

(56) **References Cited**

FIG. 7 is an enlarged cross-sectional view taken along the line 7—7 as shown in FIG. 6 thereof.
